UNITED STATES PATENT OFFICE.

VIOLA THORNE, OF GRAND RAPIDS, MICHIGAN, ASSIGNOR OF ONE-HALF TO ROMAN F. GLOCHESKI, OF GRAND RAPIDS, MICHIGAN.

ARTICLE-HOLDING CLIP.

Application filed June 13, 1927. Serial No. 198,479.

This invention relates to an article holding clip which is of very simple construction, cheaply made, easily attached to a vertical support and which may be utilized 5 to hold many and various types of articles, the article being inserted in the clip by an upward movement of said article between the gripping heads which are used to hold the article.

10 The invention is fully set forth in the following description taken in connection with the accompanying drawing, in which, Fig. 1 is a side elevation of the clip.

Fig. 2 is a front elevation thereof, and 15 Fig. 3 is a perspective view showing the clip and an article held thereby.

Like reference characters refer to like parts in the different figures of the drawing.

20 In the construction, a base plate 1 of metal is provided through which, at each end, an opening 2 is made for the passage of screws or similar fastening devices whereby it may be attached to a vertical support 25 such as a back of a seat, a wall or other convenient support.

Associated and connected with the base is a member of spring metal comprising three sections 3, 4 and 5. The upper section 30 lies flat against the upper end portion of the base 1 and is permanently secured thereto and likewise has an opening which comes into conjunction with the upper opening 2 through the base 1. The intermediate section 4 is bent outwardly and downwardly at an acute angle to the base while the lower terminal and free section 5 is bent from the lower edge of section 4 to extend vertically downward.

40 On the base 1 and at the inner side and lower end of the section 5 gripping heads 6 and 7, respectively, are permanently secured. These heads are substantially of semi-spherical form and are of metal having 45 smooth and hard surfaces. The spring material of the member attached to the base normally causes the two heads to bear with some force against each other.

The clip as thus made, as previously 50 stated, may be attached to a vertical support by screws, such as indicated at 8 in Fig. 3, inserted through the openings 2. When thus attached the article to be held may be inserted vertically between the heads 6 and 55 7. It will be noted that the lower end of

the section 5 is of semi-circular form and that it and the lower edges of the head 7 are flush so that no projections extend from the lower end of the spring member of the clip on which clothing might be caught. 60 The article to be retained by the clip is attached by forcing its upper edge upwardly between the heads 6 and 7, the spring member yielding to permit this and the heads 6 and 7 gripping the article on opposite 65 sides. It will further be noted that there is a space above the heads 6 and 7 between the base 1 and the sections 4 and 5 of the spring member, large enough to receive the rolled edge to an article, such as is present 70 many times in hats, whereby the clip is capable of holding an article of this type as well as those that are flat or have flat edges.

This clip is of particular utility at theatres 75 or the like being attached to the backs of seats. The smooth and hard surfaces of the heads 6 and 7 and their semi-spherical form render it comparatively easy to move an article upward between them. The absence 80 of any downwardly or outwardly projecting extensions to the spring member below the head 7 avoids any danger of catching of clothes or the like.

In Fig. 3 the clip is illustrated as holding a hat 9. The clip is not limited to holding hats but practically any article which can be passed between the heads 6 and 7 may be held, due account being taken of the weight of any article that it shall not 90 be so heavy as to overcome the frictional grip of the heads 6 and 7 against it. This construction of clip has proved exceptionally practical and satisfactory. The invention 95 is defined in the claims appended hereto and is to be considered comprehensive of all forms of structure coming within their scope.

I claim:

1. A clip of the class described, comprising a vertically positioned base of metal, a spring metal member attached at its upper end to said base and having an intermediate section extending outwardly and downwardly away from said base and a lower terminal free section extending vertically downward from said lower end of the intermediate section, the lower end of said terminal section being of semi-circular form, and heads of hard smooth surface material sub- 100 105 110

stantially semi-spherical in form attached one to the base and one to the inner side of the lower section of said spring member, and normally bearing against each other, the lower edge of said spring member and the lower surfaces of the head attached thereto lying flush with each other.

2. A clip of the class described, comprising a substantially flat base, a spring member attached at one end to said base and

having its other end spaced away from the base and two heads of hard, smooth surface material semi-spherical in form attached one to the base and one to the spaced away end of the spring member and normally bearing against each other, the end of the spring member and the surface of the head attached thereto being flush with each other.

In testimony whereof I affix my signature.

VIOLA THORNE.
